UNITED STATES PATENT OFFICE.

RONALD LEIGHTON SANDEMAN, OF BEARSDEN, SCOTLAND.

LOOM FOR WEAVING PILE FABRICS.

Application filed March 11, 1925. Serial No. 14,792.

To all whom it may concern:

Be it known that I, RONALD LEIGHTON SANDEMAN, a British subject, and a resident of Bearsden, in the county of Dumbarton, 5 Scotland, have invented certain new and useful Improvements in Connection with Looms for Weaving Pile Fabrics, of which the following is the specification.

The invention relates to looms for weaving cut-pile fabrics—carpets, patterned by any means, or unpatterned—and other fabrics where the pile threads are brought to the fabric as warp ends. The mechanism is of that type in which the raised pile warps 15 are received on stationary blade- or hook-like detents.

The invention has for its object to provide improved, simple and effective means for engaging the raised pile warp threads, 20 and for presenting them to the detents so that they are engaged thereby.

These warp-presenting means consist of elements (one for each warp to be operated on) moving with the sley. They may be 25 carried directly upon it or upon a separate member moved in consonance with it, during the period in which the pile loop is being formed, extend downwards between the surface warps, and are adapted each to engage, retain and release its particular thread 30 as required.

The fixed hook-like detents are so positioned that the surface warps, presented by the presenting elements, engage them and 35 pass over and are retained by their (the detents) hook-like ends when beat-up takes place, being left there when the presenting elements retire. The detents may be of the type used in prior detent mechanisms of the 40 kind referred to or may be any convenient variants thereof which will perform the required function. They may be armed with pile-loop cutting devices or any convenient form of such devices may be applied in connection with them.

It is to be understood that these presenting elements are essentially devices which, when extended between the raised surface warps, engage and retain them at the pre-determined time. Their form, the method of and means for their operation, and the manner of their carrying may clearly therefore be very widely varied.

For instance, they may consist of stiff 55 wires arranged vertically with their lower

ends bent or eccentric and pivoted vertically and side-by-side in a casing above the threads. Within the casing a cam-operated means for oscillating the wires through a sufficient arc—for instance a bar having slots 60 in it which engage cranks formed in the upper parts of the wires, mounted to slide horizontally and transversely in the box, and which is operated by the cam—may be 65 provided for this purpose.

Or such wires may be arranged at an angle other than the vertical.

Again, wires may be mounted in a rotatable spindle and their lower ends be helicoid arcs entering between the raised surface 70 warps, and of the same pitch, the partial rotation of the spindle causing them to engage and retain the threads.

Or again, helicoid discs may be so mounted 75 on a horizontal spindle.

Illustrative examples of the carrying out of the invention are shown somewhat diagrammatically on two accompanying sheets of explanatory drawings in which Figure 1 is an end elevation of the lay-out of a form 80 of operating mechanism; Figure 2 a front elevation of a part thereof; Figure 3 a cross-sectional elevation to an enlarged scale of a presenting element and its holder; Figures 4 and 5 views in elevation and plan respectively of a form of detent element; while Figures 6 and 7 are views in end elevation and front elevation respectively showing an alternative type of presenting element and the method of mounting same, and Figures 80 8 and 9 similar views of a third type of presenting element.

In the example of the lay-out of the operating mechanism shown in Figures 1 and 2, detent elements A (Figures 4 and 5) of 95 blade-like form and provided with knives A¹ each lying in a substantially vertical plane and having at their rearward projecting ends upstanding angled fingers A², are carried by a fixed transverse bar A³ parallel 100 with the breast beam A⁴ of the loom. Presenting elements B (Figure 3) of stiff wire having their lower ends B¹ bent at right angles to their axes are carried side-by-side in a casing B². On each presenting element 105 a crank B³ is formed and these cranks are engaged by the teeth of a transverse rack B⁴ also carried in the casing B². This casing B² is carried by an angle iron C secured 110 transversely to the sley C¹ which carries the

usual reed C² and is so positioned thereof that when the sley is in its forward position the presenting elements B are above and adjacent to the detent elements A. To 5 one end of the rack B⁴, and forming an extension thereof, is pivoted a link D the other end of which is pivotally connected to one end of a bell-crank lever D¹ which lever is pivotally mounted on the angle iron C. The 10 other end of the bell-crank lever D¹ is operatively connected by a link D² to one end of a tappet lever D³ which at the other end is pivoted to a fixed part of the framing. The tappet lever D³ carries a tappet D⁴ engaged by a cam D⁵. A spring E in tension 15 between a fixed part of the framing and the forward end of the tappet lever D³ keeps the tappet lever in operative contact with the cam.

20 In operation, when the sley C¹, carrying with it the casing B², moves to its rearward position (i. e. farthest away from the fell of the cloth) in order to permit the shuttle to be thrown, the lower ends B¹ of the presenting elements B lie parallel with the pile warp threads F. These threads F are raised 25 by jacquard or other known means and in rising, enter one thread between each adjacent pair of presenting elements. The contour of the cam D⁵ is such that it now depresses the tappet lever D³ and, through the link D², so moves the bell-crank lever D¹ that the rack B⁴ is constrained to move 30 in a lateral direction in the casing B² thereby turning the presenting elements B until the lower end B¹ of each element lies in a direction transverse to the threads F and touches the next adjacent element, thus closing 35 the apertures between the elements and retaining the threads therein. The sley now swings forward and the presenting elements A bring the threads F into the position shown by the chain line F¹ in Figure 1. It will be seen that the pile warp threads have 40 passed forward to a position in front of the angled fingers A² on the detent elements A. The cam D⁵ now releases the pressure on the tappet lever D³ and the spring E by means of the link D² and the bell-crank lever D¹ causes the rack to move in the 45 reverse direction, thereby turning the presenting elements B until their lower ends B¹ lie parallel with the threads which are now free to drop clear of the presenting elements. The threads are now lowered and the shuttle is passed, the threads being retained, in the form of a loop, on the detent elements A by the angled fingers A². The 50 shoot of weft is then beaten up, thus binding the loops in the usual way. These loops travel in succession along the detent element A, owing to the uptake of the cloth, until they encounter the knives A¹ and by 55 them are cut, thus forming a cut pile fabric.

60 65 In the example shown in Figures 6 and

7, the presenting elements B have their lower ends B¹ in the form of helicoid arcs and the elements are mounted side by side in a spindle G. In using this construction, the spindle G is mounted on the sley C¹ 70 (Figures 1 and 2) in place of the casing C² and a partial rotary movement is given to the spindle by a cam mechanism. This partial rotation of the spindle causes the lower ends B¹ of the presenting elements B 75 to engage and retain the threads F. Then partial rotation in the reverse direction frees the threads when they are in position over the detent elements A.

The example shown in Figures 8 and 9 80 only differs from the previous example in that the presenting elements B are in the form of helicoid discs mounted on the spindle G.

What I claim is:—

1. In looms for making pile fabrics, a sley, loop or tuft-forming mechanism comprising a set of detent elements in combination with a set of coacting presenting elements carried by and participating in the movements of the sley during the period in which the pile loops are being formed, and means to impart to said presenting elements movements independent of those participated in with the sley to cause said presenting elements each to engage, retain and release its particular thread and place it on a detent element.

2. In looms for making pile fabrics, a sley, and loop or tuft-forming mechanism 100 comprising a set of detent elements in combination with a set of coacting presenting elements carried by and adapted to move in consonance with the sley during the period in which the pile loops are being formed, and means to impart to said presenting elements oscillatory movements independent of the movements participated in with the sley to cause the presenting elements each to engage, retain and release 105 its particular thread and place it on a detent element.

3. In looms for making pile fabrics, a sley, and loop or tuft-forming mechanism comprising a set of detent elements in combination with a set of coacting presenting elements carried by and bodily movable with the sley during the period in which the pile loops are being formed, and means including a cam for imparting to said presenting elements movements of partial rotation independent of their bodily movements to cause said presenting elements each to engage, retain and release its particular thread and place it on a detent element.

4. In looms for making pile fabrics, a sley, and loop or tuft-forming mechanism comprising a set of detent elements in combination with a set of coacting presenting elements adapted to move in consonance 130

with the sley during the period in which the pile loops are being formed, and means adapted to cause the presenting elements

each to engage, retain and release its particular thread and place it on a detent element, said means comprising a crank on each presenting element, a rack engaging

these cranks, and a cam-operated lever adapted to give lateral movement to the rack.

In testimony whereof I have signed my name to this specification.

RONALD LEIGHTON SANDEMAN.
